Primary Examiner — Kevin K. Rudzinski*Assistant Examiner* — J. Thorn, Sr.(74) *Attorney, Agent, or Firm* — Cislo & Thomas, LLP(57) **CLAIM**

The ornamental design for a hooded garment, as shown and described.

DESCRIPTION

FIG. 1. is a perspective view of my hooded garment;
FIG. 2. is a front view thereof;
FIG. 3. is a right side view thereof;
FIG. 4. is a left side view thereof;
FIG. 5. is a back view thereof;
FIG. 6. is a top view thereof;
FIG. 7. is a bottom view thereof;
FIG. 8. is a front view thereof with the sleeves down; and,
FIG. 9. is a rear view thereof with the sleeves down.
The broken lines shown in the drawings depict environment that forms no part of the claimed design.
